[57] CLAIM

The ornamental design for electrocardiographic re--
cording paper, as shown and described.

DESCRIPTION

FIG. 1 is a top plan view of an electrocardiographic
recording paper showing my new design;

FIG. 2 is an enlarged top plan portion of the recording
paper, shown for clarity of illustration;

FIG. 3 is a side elevation of FIG. 1; and

FIG. 4 is a rear elevation thereof.

The undisclosed bottom portion of the recording paper
is plane and unornamented.

FIG. 4.

FIG. 2.
